H. M. HOWELL

EASEL

Filed Jan. 6, 1925

Fig. 1.

Patented May 26, 1925.

1,539,488

UNITED STATES PATENT OFFICE

HELEN M. HOWELL, OF LOS ANGELES, CALIFORNIA.

EASEL.

Application filed January 6, 1925. Serial No. 815.

To all whom it may concern:

Be it known that I, HELEN M. HOWELL, a citizen of the United States, residing at Los Angeles, in the county of Los Angeles and State of California, have invented certain new and useful Improvements in Easels, of which the following is a specification.

The invention relates to easels, and has as an object the provision of an easel, more particularly adapted to the use of students in classes, such as kindergarten classes.

A further object of the invention is the provision of an easel which may be folded flat, so as to permit of a number of easels being stacked in a compact pile one upon another.

A further object of the invention is the provision of an easel having a drawer for the reception of drawing materials, which drawer has means for preventing its undesired escape from the easel, but which may be readily removed when it is desired to fold the easel.

A further object of the invention is the provision of an easel having means for holding one or more sheets of paper whereby sheets may be readily replenished and torn off or thrown out of the way when used.

Further objects of the invention will appear from the following description when read in connection with the accompanying drawing showing an illustrative embodiment of the invention and wherein:

Fig. 1 is a front elevation.

Fig. 2 is a central vertical section on line 2—2 of Fig. 1.

Fig. 3 is a like view of the easel folded.

Fig. 4 is a rear elevation of the easel with the drawer in place, and

Fig. 5 is a horizontal section on broken line 5—5 of Fig. 2.

As shown, the easel comprises front legs 10 and 11, preferably held in parallel relation to each other, as by means of cross pieces 12, 13.

Rear swinging legs 14, 15, also arranged parallel to each other, are shown as hinged to the cross member 13, as at 16, 17. The rear legs may be held in spaced relation by means of the hinges at their tops, and by means of the cross member 18 adjacent their lower ends. The spacing of the legs 14, 15 is such that they will fold between the legs 10, 11, and the cross member 18 is placed in such a position as to fold into the plane of

the cross member 12, as clearly shown in Fig. 3.

To prevent the legs 14, 15 from slipping when the easel is in use there is shown a brace member 19 hinged to the cross member 12, as at 20, and having sliding engagement with the legs 14, 15. To provide such sliding engagement a stud 21, 22 is provided adjacent each rear corner of the brace member 19, which studs project into grooves 23, 24 formed in the inwardly directed edges of the legs 14, 15. To hold the brace member 19 from dropping below the horizontal position when the easel is extended a stop member may be placed in each of the grooves 23, 24. This stop member is shown in the drawing as in the form of pins 25, 26 driven into the bottoms of the grooves 23, 24. It will be understood that any other form of a stop member may be utilized, as for instance a termination of the grooves 23, 24, at the appropriate point. The width of the brace member 19 is sufficient to allow the same to fold between the legs 14, 15, and into the plane thereof, and of the legs 10 and 11 when the easel is collapsed.

To support a drawer 27 the brace member 19 is preferably made of an unbroken piece of material, and the drawer is made of a length to slide freely between the legs 10 and 11 and upon the upper surface of the brace 19. The angle of the front 28 of the drawer is made to equal the angle of the front of the easel when erected, and the front will therefore lie in the plane of the cross member 12. The ends of the front 28 are shown as extended beyond the body of the drawer so as to overlap the legs 10 and 11 to prevent the drawer being forced too far to the rear.

To prevent the drawer from being inadvertently pulled free of the easel when drawn out to secure access to its contents, pins 29, 30 are provided projecting downwardly from the rear wall 31 of the drawer. Since the length of the drawer is equal to the space between the legs 10 and 11 the pins may be placed in a position spaced inwardly from the ends of the drawer and may project downwardly at each edge of the brace member 19, as clearly illustrated in Fig. 5.

The drawer may be removed by pulling the same out until the pins contact with the cross member 12, and then by dropping the

front of the drawer down until the pins may be disengaged from the cross member. To prevent such action when not desired latch members 32, 33 are shown as pivoted at 34, 5 35, to the inner surface of the rear wall 31 of the drawer. When it is desired to remove the drawer the latch members 32, 33 may both be turned to the position shown for the latch member in Fig. 4, in which position they will fall below the plane of the 10 upper edge of the drawer, and the drawer may therefore be removed, and the drawers for the easels of the entire class may be stacked in compact piles.

15 To conveniently retain paper 36, there are shown a pair of pins 37, 38 rigidly secured to the cross member 13, and projecting therefrom, over which openings in the paper may be slipped. To retain the paper upon 20 the pins there is shown a bar 39, which bar may be retained in position by means of spring fingers 40, 41, pivoted to a member 42 superposed upon the upper edge of the cross member 13. The thickness of the 25 member 42 is desirably equal to the thickness of the bar 39 plus the thickness of the greatest amount of paper which it is desired to hold upon the easel at any one time.

Desirably a sheet of heavy card 43 may 30 be placed upon the pins 37, 38 to serve as a drawing board for the lowest sheet of paper. The bar 39 may be removed by swinging both of the fingers 41, 42 to the position shown for the finger 41, in Fig. 1. To avoid 35 misplacement of the bar 39 it is shown as flexibly secured to the member 42 by means of chains 44, 45.

The easel when folded falls into a compact rectangular space, and a large number 40 of easels may be piled one upon another without danger of the pile being upset because of any unevenness of its constituents. Because of the construction whereby the swinging end of the cross brace member is 45 guided in a groove in the back brace member, the cross member readily falls to its position when the back member is swung rearwardly. This facility of operation is of importance in the use of the easel by kindergarten classes, since the easel may be readily erected without confusion or unnecessary noise, or waste of time.

Due to the position of the brace member 50 well down toward the ends of the upright members the easel is very stable and is not easily upset while in use. Moreover the

easel because of its construction is not expensive to manufacture, and is efficient in use. The drawer is not likely to be accidentally withdrawn so as to cause confusion by spilling of its contents. Minor changes may be made in the physical embodiment of the invention without departing from its spirit.

I claim:

1. An easel comprising, in combination, spaced parallel main legs, cross members superposed on said main legs adjacent the upper and the lower ends thereof to retain the same in fixed relation, spaced parallel brace legs pivotally connected to the said main legs adjacent the top thereof, the outer edges of said brace legs being adapted to fall between the inner edges of the main legs, a cross member superposed on the lower ends of said brace legs and being adapted to fall into the plane of and below the lower first-named cross member when the easel is folded, a brace, narrower than the distance between said brace legs, pivoted to said lower first-named cross member and having upwardly sliding connection with respect to the inner edges of said brace legs, and means on the upper end of said easel to hold the article to be supported thereon, lying between and in the thickness of said first-named cross members. 75

2. An easel comprising, in combination, spaced parallel main legs, cross members superposed on said main legs adjacent the upper and the lower ends thereof to retain the same in fixed relation, spaced parallel brace legs pivotally connected to the said main legs adjacent the top thereof, the outer edges of said brace legs being adapted to fall between the inner edges of the main legs, a cross member superposed on the lower ends of said brace legs and being adapted to fall into the plane of and below the lower first-named cross member when the easel is folded, a brace, narrower than the distance between said brace legs, pivoted to said lower first-named cross member and having upwardly sliding connection with respect to the inner edges of said brace legs, means on the upper end of said easel to hold the article to be supported thereon, lying between and in the thickness of said first-named cross members, and a removable drawer, supported and sliding on said brace member and between said main legs. 100

HELEN M. HOWELL.
